LENGTH BAR FOR MICROMETER GAUGES
AND THE LIKE

Leonard Ernest Glover, Leatherhead, England,
assignor to himself and Pitter Gauge & Precision Tool Co. Limited, Leatherhead, England,
a company of Great Britain

Application July 28, 1944, Serial No. 546,993
In Great Britain August 14, 1943

6 Claims. (Cl. 33—168)

1

This invention relates to linear-dimension gauges and it refers more particularly to a length bar for use as or with a linear-dimension gauge. Such length bars may be employed with a micrometer end to enable one such micrometer end to be used in gauges of varying lengths.

The length bars are provided in varying lengths so that by securing two or more together any desired length of gauge may be produced. The ends of each bar are carefully lapped and when two length bars are secured the adjacent lapped faces accurately bed together. Various constructions are known for effecting the securing together of adjacent length bars and particularly desirable constructions are described in the specification of the copending application Serial No. 546,992.

In handling the length bars their dimensions may be affected by the heat of the hands or the body of the user and in order to overcome such difficulties it has been proposed to provide the bar with a protective covering which may be of either a heat insulating or non-insulating material.

According to the present invention a length bar for use as or with a linear-dimension gauge has a surrounding protective tube so mounted as to be spaced from the face of the bar. An air gap is thus formed between the tube and the bar which will prevent transmission of heat between the protective tube and the bar.

Preferably the protective tube is mounted to have slight longitudinal and/or circumferential movement in relation to the bar.

One form of length bar according to the present invention and for use with an internal micrometer gauge will now be described by way of example and with reference to the accompanying drawing which shows the length bar partly in section.

The length bar comprises a piece of steel tube 1 of definite and accurate length between its end faces 2, 3. These faces are hardened and are lapped to produce great accuracy. The bar is provided at its ends with means for attachment to another bar. Thus, for example, it has one end internally threaded at 4 and a threaded plug member 5 mounted at the other end. Said threaded plug member is illustrated as having freedom of movement in all directions and is of the form described in the specification of the copending application Serial No. 546,992. A ferrule 9, which may be of metal but is preferably of a heat insulating material, and having a knurled surface is fitted loosely on to each end of the tube 1. Each ferrule is held in place by a

2

tapered pin 10 passing through holes in the wall of the ferrule and holes in the wall of the tube. The holes in the wall of the tube are slightly larger than the pin so that distortion in assembling is prevented.

The adjacent ends of the ferrules are recessed at 11 to accommodate a protective tube 12. This tube is preferably of heat-insulating material, such as bitumenised paper but it will be understood that other materials may be employed. The diameter of the recesses is such that the protective tube will have slight play therein and the length of the tube is a little less than the distance between the bottoms of the recesses in the ferrules as is shown in the drawing. The tube can thus move circumferentially and also slightly longitudinally in relation to the bar. The internal diameter of the tube 12 is greater than that of the bar 1 so that an air gap 6 is formed between the tube and the bar. In this way when the bar is handled heat of the hands or the body of the user will not be transmitted directly to the bar. Further, as the protective tube is free in relation to the bar the latter can only be assembled with like bars by handling by means of the ferrules 9. This avoids twisting or distortion of the length bars, particularly the longer ones. By arranging for the tube 12 to have a slight movement in relation to the bar any change in the length of the tube due to change of temperature or humidity conditions will not be transmitted to the bar itself.

The length bar may be used with all kinds of length measuring apparatus, such as micrometer gauges in which the position of an anvil or like bearing surface is controlled by a screw or by other means such as a pack of accurately dimensioned blocks, for example slip gauges, or in which it is movable and attached to indicating mechanism.

What I claim is:

1. A length bar for use in gauging lengths, means carried on said length bar for connecting it to another gauging member, said length bar having the end faces thereof accurately finished in a plane at right angles to the axis of the bar, and a protective tube surrounding said length bar and spaced therefrom to provide an air space between the bar and the protective tube, and said protective tube being mounted in such manner that it is capable of movement relative to the length bar.
2. A length bar for use in gauging lengths,

means carried on said length bar for connecting it to another gauging member, said length bar having the end faces thereof accurately finished in a plane at right angles to the axis of the bar, and a protective tube surrounding said length bar and spaced therefrom to provide an air space between the bar and the protective tube, and said protective tube being mounted in such manner that it is capable of longitudinal and circumferential movement relative to the length bar.

3. A length bar for use in gauging lengths, means carried on said length bar for connecting it to another gauging member, said length bar having the end faces thereof accurately finished in a plane at right angles to the axis of the bar, and a protective tube of heat insulating material surrounding said length bar and spaced therefrom to provide an air space between the bar and the protective tube, and said protective tube being mounted in such manner that it is capable of movement relative to the length bar.

4. A length bar for use in gauging lengths, means carried on said length bar for connecting it to another gauging member, said length bar having the end faces thereof accurately finished in a plane at right angles to the axis of the bar, and a protective tube of heat insulating material surrounding said length bar and spaced therefrom to provide an air space between the bar and the protective tube, and said protective tube being mounted in such manner that it is capable of

longitudinal and circumferential movement relative to the length bar.

5. A length bar for use in gauging lengths, means carried on said length bar for connecting it to another gauging member, said length bar having the end faces thereof accurately finished in a plane at right angles to the axis of the bar, ferrules fitted on each end of the bar provided with recesses at the adjacent ends thereof, and a protective tube loosely supported at its ends in the recesses provided in the ferrules, to thereby provide for longitudinal and circumferential movement of the protective tube relative to the bar.

6. A length bar according to claim 5, wherein the ferrules are fitted on the bar by means of pins passing through slightly larger holes in the bar.
